(57) **CLAIM**

The ornamental design for a strapping device, as shown and described.

DESCRIPTION

FIG. 1 is a perspective view of one embodiment of a strapping device of the present invention;

FIG. 2 is a front elevational view of the strapping device of FIG. 1;

FIG. 3 is a rear elevational view of the strapping device of FIG. 1;

FIG. 4 is a left side elevational view of the strapping device of FIG. 1;

FIG. 5 is a right side elevational view of the strapping device of FIG. 1;

FIG. 6 is a top plan view of the strapping device of FIG. 1;

FIG. 7 is a bottom plan view of the strapping device of FIG. 1;

FIG. 8 is a perspective view of the strapping device of FIG. 1 in which the strap has been removed for clarity.

FIG. 9 is a front elevational view of the strapping device of FIG. 1 in which the strap has been removed for clarity;

FIG. 10 is a rear elevational view of the strapping device of FIG. 1 in which the strap has been removed for clarity;

FIG. 11 is a left side elevational view of the strapping device of FIG. 1 in which the strap has been removed for clarity;

FIG. 12 is a right side elevational view of the strapping device of FIG. 1 in which the strap has been removed for clarity;

FIG. 13 is a top plan view of the strapping device of FIG. 1 in which the strap has been removed for clarity; and,

FIG. 14 is a bottom plan view of the strapping device of FIG. 1 in which the strap has been removed for clarity.

The broken line showing of FIGS. 1-14 is for the purpose of illustrating the environmental structure and form no part of the claimed design.
